UNITED STATES PATENT OFFICE.

STANLEY H. LINDGREN, OF MAYWOOD, ILLINOIS, ASSIGNOR TO AMERICAN CAN COMPANY, OF NEW YORK, N. Y., A CORPORATION OF NEW JERSEY.

SHOE-POLISH BOX.

Application filed October 10, 1921, Serial No. 508,748. Renewed October 17, 1924.

To all whom it may concern:

Be it known that I, STANLEY H. LINDGREN, a citizen of the United States, residing in Maywood, in the county of Cook and

5 State of Illinois, have invented a new and useful Improvement in Shoe-Polish Boxes, of which the following is a specification.

This invention relates to containers, and more particularly to improved means for 10 opening a container of the general type ordinarily used as a receptacle for shoe polish and like material.

A principal object of the invention is the provision of an opening device permanently 15 secured in a part of the container in such manner as to interfere in no way with the closing of said container, and easily operated by the fingers to effectively remove the cover.

20 Another object of the invention is the provision of a shoe polish box construction formed in particularly suitable manner to provide effective leverage between the cover and the box body.

25 Another object of the invention is the provision of a simple and inexpensive opening device for a container of the character stated which, by reason of its formation, is adapted to operate with a cam action on the customary limiting ridge of the container body, and to be readily returned and retained in 30 inoperative position.

Still another object of the invention is the provision of an opening device suited for 35 use with a container of simple construction, requiring but very slight special formation and capable of manufacture by a few and simple mechanical operations.

40 Numerous other objects and advantages of the invention will be apparent as it is better understood from the following description, which, taken in connection with the accompanying drawings, discloses a preferred embodiment thereof.

45 Referring to the drawings,

Figure 1 is a top plan view of a container constructed in accordance with my invention;

50 Fig. 2 is a side elevation thereof showing the opening device in inactive position;

Fig. 3 is a similar view after operation of the device, showing the action thereof;

Fig. 4 is a fragmentary detail of a portion of the cover showing the part of the

flange through which the opener is adapted 55 to operate; and

Fig. 5 is an enlarged perspective view of the opener showing its construction.

The container, upon which my invention is employed, comprises a body 11 and a 60 domed cover 12 having a depending flange 13 adapted to frictionally engage the upper part 14 of the container body to close the package. The body is provided, beneath the part 14, with a flange or limiting ridge 15 65 extending circumferentially thereabout and providing a substantially flat ledge for co-operation with parts now to be described.

Extending outwardly from the flange 13 is a lateral extension or flange part 16 of 70 substantially corresponding size and formation with a ledge 15. This flange part, when the container is closed, matches with said ledge 15 and rests thereon throughout the greater part of its circumference, thus providing a tight hermetic closure. The parts are so formed that the container may be closed by merely pressing the cover or cap 12 upon the body part 14 to the extent permitted by the ledge or limiting ridge 15. 75

The flange part 16 is formed with a slightly elevated or humped-up part 17 having therein apertures 18 for the retention and pivoting of a wire opener 19. The part 17 is formed by bending the flange part 16 upwardly at 21 and 22, the material of the flange 13 being cut away between these points. The opener 19 is formed of wire 80 bent to form a substantially continuous rectangle having a bottom part 23 adapted to rest upon the ledge 15, side parts 24 and 25 extending upwardly through the apertures 18 and a top part 25 completing the rectangle. An extension 26 is twisted to form 85 an outwardly extending thumb piece whereby the opener may be operated and has its end 27 returned to within the square or rectangular part of the device. The apertures 18 are somewhat elongated to permit 90 turning of the opening device 19 therein, and when so turned, one of the angles 28 is caused to bear upon the ledge 15 with a cam action whereby the container is opened. It 95

will thus be seen that the part 17 retains the opener in inactive position, a space being provided between said part and the ledge 15 for the bottom 23 of the rectangular part of the member 19. Said part 19 operates 100 105

through the flange part 17 as a pivot and provides leverage upon the cover whereby the latter may be effectually removed with but slight effort.

5. It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

15. I claim:

1. A container, comprising a body part having a wall provided with a limiting ridge beneath the top thereof, a cover adapted to frictionally engage the upper part of said wall and provided with an outwardly turned flange having an apertured humped portion with apertures in the top thereof, and an opening device extending down through the apertures in said humped portion and having a cam action on said limiting ridge to open the container.

2. A container, comprising a body part having an upstanding wall provided beneath its top with an outwardly extending ledge, a cover adapted to frictionally engage the upper part of said wall and having a flange in substantial registration with said ridge when the container is closed, a portion of said flange being elevated and having apertures therein, and an opening device extending through said apertures and providing leverage on said cover with said ledge as a base to remove the cover.

3. A container, comprising a body part having a ledge extending thereabout, a cover frictionally engageable with said body part above said ledge and having an outwardly turned flange having apertures in a portion thereof, and a wire opening device having a part of substantially square form revoluble in said apertures to remove the cover by cam action upon said ledge.

4. A container, comprising a body part having a ledge extending thereabout, a cover frictionally engageable with said body part above said ledge and having an outwardly turned flange having apertures in

a portion thereof, and a wire opening member adapted to be turned through said apertures and having an irregular part exerting leverage on said cover with said ledge as a base to remove the cover.

5. A container, comprising a body part having a ledge extending thereabout, a cover frictionally engageable with said body part above said ledge and having an outwardly turned flange having apertures in a portion thereof, and a wire opening device having an irregular part adapted to be turned through said apertures to provide leverage between said cover and said ledge, said opener having a lateral extension for operation thereof.

6. A container, comprising a body part having a wall provided with a ledge beneath its top, a cover having a flange adapted to frictionally engage the upper part of said wall and having an outward extension resting upon said ledge when the container is closed, said extension having an apertured elevated portion and an opening device of angular formation extending through said apertures and adapted to be turned to force the cover from frictional engagement with said wall.

7. A container, comprising a body part having a wall provided with a limiting ridge beneath the top thereof, a cover adapted to frictionally engage the upper part of said wall and provided with an outwardly turned humped-up and apertured flange, and a substantially rectangular opening device secured in the apertures in said flange and adapted to be turned to exert a cam action upon said ridge to open the container.

8. A container, comprising a body part having a wall provided with a limiting ridge below the top thereof, a cover adapted to frictionally engage the upper part of said wall above said ridge and provided with an outwardly turned flange having apertures therein, and an opening device extending through both of said apertures and having a rotary movement therein and provided with a cam adapted to bear on said ridge to open the container when the opening device is turned.

STANLEY H. LINDGREN.
